UNITED STATES PATENT OFFICE.

MORLEY CHESTER ZAVITZ, OF ALVINSTON, ONTARIO, CANADA.

TRACTOR PLOWING ATTACHMENT.

Application filed May 18, 1925. Serial No. 31,004.

To all whom it may concern:

Be it known that I, MORLEY CHESTER ZAVITZ, of the village of Alvinston, in the county of Lambton and Province of Ontario, Canada, have invented certain new and useful Improvements in Tractor Plowing Attachments, of which the following is a full, clear, and exact description.

The object of my invention is to produce a plowing attachment in connection with tractors, capable of easily moving the plows sideways so as to straighten the furrows without altering the course of or stopping the tractor.

A further object of my invention is to obtain a wide range of action for the machine and to cause the same to be rigid when not in use.

A still further object of my invention is to construct a machine of simple form, where all the parts are readily accessible either for repairs or inspection.

In the accompanying drawings, similar reference symbols refer to similar parts throughout the several views.

Figure 1 is a front elevation of my attachment as it appears when detached from a tractor.

Figure 2 is a vertical section on line 2—2, Figure 1.

Figure 3 is a horizontal section on line 3—3, Figure 2.

My attachment comprises a plate 1 carrying at each end guide members 2, each consisting of a metal bar bent upon itself so as to leave an opening 3 of sufficient width between its parallel sides to form a guideway, for a purpose hereinafter described. The open end of said opening is positioned over the end of plate 1 so as to straddle the same and is there bolted as at 4. The guide member 2 has its lower side end bent at right angle to form an ear 5 having a perforation 6 to allow the attachment to be bolted to the tractor frame 7 by means of a bolt 8.

In the openings 3 of the guide members 2, I mount a metal bar 9 having its ends bent upwards to form uprights 10 and 11, each carrying a hook 12 bolted therethrough. It will be noticed that the hook 12 on upright 10 is higher from the bar 9 than the hook 12 on upright 11 a distance sufficient to permit the two ends of a chain coiled around a post hereinafter described to remain horizontal when hooked thereto.

In order to take up the friction of the bar

9 from the sides of openings 3, I mount friction wheels 13 against which the bar travels.

To lock bar 9 in any position, I provide along its face perforations 14 so positioned as to coincide with a perforation 15 in one of the guide members 2, which member carries a locking bolt 17 consisting of a member 16 having one end bent to enter perforation 15, and its opposite end bent to form a foot 65 pedal 18. Member 18 is fulcrumed at 19 in a lug 20 on guide plate 2. A spring 21 is mounted to normally keep bolt 17 of member 16 in perforation 15. Bar 9 has a perforation 22 positioned centrally thereof where 70 the draw-bar of the plow may be connected.

To obtain the sidewise movement of bar 9, I provide a post 23 mounted vertically on base plate 1. In the present showing, the mounting comprises a plate 24 offset at 25 so 75 as to form an opening 26. The offset portion 25 is perforated to allow post 23 to rotate therein. A pin 27 passes through post 23 to keep the same in position. Plate 24 is attached to plate 1 by means of bolts 35 80 passing through said plates and through a part of the tractor, serving the double purpose of holding plate 24 in position and the attachment on the tractor. This attachment, together with the ears 5 form a rigid 85 connection to the tractor. I brace the upper end of post 23,—first on one side by a double brace 28 fastened to guide members 2, the same having a collar 29 around the post as shown, and second, on the other side by a bar 90 30 also having a collar 31 around the post. The other end of bar 30 is fastened to any suitable place on the tractor. Over the braces aforementioned, I fix on post 23 an operating wheel 32 to rotate said post. On 95 post 23 between the hooks 12 on uprights 10 and 11, I wind a few turns of a chain 33 and extend the ends to the hooks 12. One of the links of said chain is fastened to post by a bolt 34.

In operation, the attachment having been securely fastened to the tractor as previously explained, the plow beam is connected to the bar 9 at 22. The adjusting wheel 32 is positioned on the tractor near the seat of the operator and when it is desired to shift bar 9, he presses on pedal 18, which will remove bolt 17 from the perforations in the bar and allow the free movement of bar 9 whenever post 23 is rotated. This movement is obtained by the chain 33 winding on post 23 when wheel 32 is turned. The

shifting of bar 9 will cause the plow to move either way and thus the furrows may be straightened without stopping the tractor.

The attachment shown is one selected 5 among many types working on the same principle. It should be understood that the following claims are not limited solely to the present showing but may vary within a reasonable scope.

10 What I claim as my invention and desire to secure by Letters Patent is—

1. In a tractor attachment of the class described, a base plate, guideways mounted one at each end of said base plate, a bar 15 mounted to move longitudinally in said guideways, antifriction means in said guideways upon which said bar moves, integral standards mounted one at each end of said bar, hooks in said standards, a post mounted at right angles to said base plate centrally thereof, means on said base plate to form a bearing for said post, means to brace said post at its upper end, hand-operated 20 means to turn said post, a chain wound around said post having its ends connected to the hooks of the standards aforesaid, means to attach said attachment to a tractor comprising bolts passing through the base 25 plate and ears integral with the guideways.

to the hooks of the standards aforesaid, and bolts passing through said plates to connect said attachment to the tractor.

2. In a tractor attachment of the class described, a base plate, guideways mounted 30 one at each end of said base plate, a bar mounted to move longitudinally in said guideways, antifriction means in said guideways upon which said bar moves, integral standards mounted one at each end of said bar, hooks in said standards, a post mounted at right angles to said base plate centrally thereof, means on said base plate to form a bearing for said post, means to brace said post at its upper end, hand-operated 40 means to turn said post, a chain wound around said post having its ends connected to the hooks of the standards aforesaid, means to attach said attachment to a tractor comprising bolts passing through the base 45 plate and ears integral with the guideways.

In testimony whereof, I have hereunto affixed my signature, this 6th day of August, 1924.

MORLEY CHESTER ZAVITZ.
